HYDROCARBON GAS FUEL TORCH Cadet E. Bowman, Sycamore, Ill., assignor to
Olin Corporation

Filed Nov. 19, 1971, Ser. No. 200,651

Term of patent 14 years

Int. Cl. D8—05

U.S. Cl. D8—30

FIG. 3FIG. 1 is a side elevational view of a hydrocarbon gas fuel torch embodying my new design;

FIG. 2 is a right hand end view of the torch of FIG. 1; and

FIG. 3 is a top view of a torch of FIG. 1.

The broken line showing of a portion of a fuel container is for illustrative purposes only.

I claim:

The ornamental design for a hydrocarbon gas fuel torch, as shown and described.
